UNITED STATES PATENT OFFICE.

DAVID GREENBERG, OF NEW YORK, N. Y.

DESIGN FOR A GEM-SETTING.

50,128.

Specification for Design.

Patented Jan. 2, 1917.

Application filed September 25, 1916. Serial No. 122,161. Term of patent 7 years.

To all whom it may concern:

Be it known that I, DAVID GREENBERG, a citizen of the United States, who resides in New York city, county and State of New York, have invented a new, original, and ornamental Design for Gem-Settings, of which the following is a specification, reference being had to the accompanying drawings, forming part thereof.

Figure 1, of the drawings is a side elevation, Fig. 2, is a top plan view and Fig. 3, is an under side view of a wire-like gem setting showing my design.

This design is applicable to lavallières, rings, bracelets, necklaces and other jewelry.

I claim:

The ornamental design for a gem setting as shown.

In testimony whereof, I have hereunto set my hand in the presence of the two subscribing witnesses.

DAVID GREENBERG.

Witnesses:

WILLIS FOWLER,
EDITH A. KLAUS.
